UNITED STATES PATENT OFFICE.

AUGUST NICOL, OF BERLIN, GERMANY, ASSIGNOR TO BERGMANN ELEKTRICITATS-WERKE AKTIENGESELLSCHAFT, OF BERLIN, GERMANY, A CORPORATION OF GERMANY.

CHANGEABLE-RATE ELECTRICITY-METER.

No. 920,623.

Specification of Letters Patent.

Patented May 4, 1909.

Application filed December 14, 1907. Serial No. 406,475.

To all whom it may concern:

Be it known that I, AUGUST NICOL, a subject of the Emperor of Germany, and resident of Berlin, Germany, have invented certain new and useful Improvements in Changeable - Rate Electricity - Meters, of which the following is a specification.

My invention relates to electricity meters, and has for its object to provide a simple device for automatically changing the rate registered per kilowatt-hour at certain times of the day or night. It is customary in some countries to charge more for electricity during the evening hours than at other times.

My apparatus will effect the desired changes automatically at the proper time.

A typical example of my invention is shown in the accompanying drawings, Figure 1 being an elevation of the apparatus with parts in section, and Fig. 2 a face view thereof, with parts broken away.

A indicates a shaft which is mounted to turn and is also capable of sliding lengthwise in the stationary dial-plate G and the clock work plate G'. By means of gearing M, V, driven from the clock-work U, the shaft A is given one revolution in twenty-four hours. The shaft is also movable lengthwise in its bearings, being pressed toward the plate G, by a spring F. A hand B and a cam arm C are rigidly secured to the shaft A, the gear M also being rigid on said shaft, and the gear V is of sufficient width to keep both gears in engagement notwithstanding any longitudinal movement of the shaft A.

The dial plate G is provided with a series of holes G² preferably screw-threaded and located at regular intervals (half-hour intervals as shown). The central panel of the dial may bear the designations "Day" and "Night." Into the holes G² may be inserted pins or screws E adapted to engage, with their projecting inner ends, the beveled end portion D of the cam arm C. The pins E will therefore force the shaft and the wheel M back (to the right in Fig. 1) when the cam arm engages said pins. Preferably the arm should engage one pin before it leaves the preceding pin, so as to keep the wheel M in the same position lengthwise of the shaft A on that portion which is fitted with pins E. Where no pins are inserted (see the lower portion of the dial in the drawings) the spring

F will bring the wheel M as far as it will go 55 toward the dial-plate G.

The changing position of the disk or wheel M is utilized to throw into operation one or the other of two indicating or registering trains of gearing. The shifting mechanism 60 illustrated comprises a lever I fulcrumed at I' and carrying a wheel H adapted to roll on the face of disk or wheel M and to follow said wheel as it moves toward or from the dial-plate G. A spring L presses the wheel H 65 against the wheel M. Another spring L' connects the lever I with a crank arm K' on a rock shaft K journaled in bearings K². This rock shaft governs the indicator or registering device of the meter in any well-known or approved manner, that is, with the wheel M in the "day" position, a different (lower) rate per hour will obtain than during the night hours.

It will be observed that the hand B serves 75 as a time-hand (hour-hand) and also shows in connection with the screws or pins E during what hours a particular rate is in force. The device is very simple and inexpensive, and does not require a particularly strong 80 clockwork.

The particular device shown in the drawing for registering or indicating different rates according to the position of the wheel M is as follows: On the rockshaft K is secured rigidly an arm or stop W adapted to engage and hold one or the other of two toothed wheels N, N'. (Only a portion of the wheel N' is shown in Fig. 2.) The wheels N, N' are mounted to turn independently about the same axis, and each of them is rigidly connected with a gear wheel F, F'. Both wheels F, F' are in engagement with a pinion O' rotating about an axis disposed radially with respect to the shaft O which carries an arm O² on which said pinion is journaled. The wheel N is in permanent connection with the train of gearing P constituting an indicator or register, and the wheel N' is in permanent connection with a 95 similar indicating or registering device Q. The shaft O is driven from the motor part of the meter, for instance from the rotary disk T' by means of a worm S on the shaft T of said disk engaging a worm wheel R on the shaft O. A balance weight O³ may be applied to the arm O².

It will be understood that according to the

position of the arm W one or the other of the wheels N, N' and of the indicating or registering trains P, Q, respectively will be held stationary, the other being operated by the motor of the meter. It is of course understood that the two indicators are different, corresponding to the two rates employed, that is the indication of one of said devices P, Q for say one thousand revolutions of the shaft T, will be higher than the indication of the other device for the same number of revolutions of the shaft T.

While I have described the invention as applied to an electricity meter, it is obvious that it may be used wherever it is desired to charge different rates for certain commodities, work, or services, at different times of the day or night, and I therefore give a broad meaning to the word "meter" as employed in the claims.

I claim:

1. In a meter, the combination of a rotary member capable of moving lengthwise of its axis of rotation, stationary movable pins arranged at equal distances from said axis arranged to engage said member and controlling its position lengthwise of said axis, and shifting means actuated by the longitudinal movement of said member.
2. In a meter, the combination of the rotary disk capable of moving lengthwise of its

axis of rotation, the cam arm rigidly connected with said disk, a dial plate provided with a series of openings located at equal distances from said axis, pins adapted to be inserted in said openings and to project into the path of said arm, a spring for pressing the arm toward the pins, and shifting means engaging said disk and controlled by its longitudinal movement.

3. In a meter, the combination of the rotary shaft and the hand carried thereby, the stationary dial-plate on which said hand is adapted to indicate, a disk mounted to turn with the shaft, but movable lengthwise thereof, a cam arm rigidly connected with said disk, projections extending from the dial-plate toward the cam arm and adapted to engage the same, a spring for pressing the cam arm toward the dial-plate, a lever engaging said disk and actuated by a longitudinal movement thereof, and mechanism controlled by said lever.

In testimony whereof I have hereunto signed my name in the presence of two subscribing witnesses this 29th day of November, 1907.

AUGUST NICOL.
